W. H. FAIRCHILD

PLASTER BASE

Filed May 10, 1922

Walter H. Fairchild
by Fred Gerlach his Petty
friend

UNITED STATES PATENT OFFICE.

WALTER H. FAIRCHILD, OF CHICAGO, ILLINOIS, ASSIGNOR TO MID-WEST BOX COMPANY, OF ANDERSON, INDIANA, A CORPORATION OF INDIANA.

PLASTER BASE.

Application filed May 10, 1922. Serial No. 559,756.

To all whom it may concern:

Be it known that I, WALTER H. FAIRCHILD, a citizen of the United States, and a resident of Chicago, in the county of Cook and State of Illinois, have invented certain new and useful Improvements in Plaster Bases, of which the following is a full, clear, and exact description.

The invention relates to plastering bases and its object is to provide an improved base which serves to efficiently retain the plaster without waste, may be readily applied to the usual studs of a building, and which is inexpensive in cost.

The invention consists in the several novel features hereinafter set forth and more particularly defined by claims at the conclusion hereof.

In the drawings: Fig. 1 is a perspective of a portion of a wall embodying the invention. Fig. 2 is a horizontal section. Fig. 3 is a vertical section.

The invention consists in forming a plastering base of a sheet of woven wire lath consisting of strips of wire 11 connected by strips 15 woven obliquely back and forth and wrapped around the strips 11 and a backing formed of corrugated board. This backing comprises a back liner or facing 7, a front liner or facing 8, an intermediate corrugated sheet 9, and a corrugated sheet 10 secured to the front face of the front liner 8. These liners and corrugated sheets are all permanently secured together to form a stiff double faced corrugated board which is waterproofed by immersing it in a suitable solution of asphaltum after or before the liners and corrugated sheets have been united by a suitable adhesive. The woven wire lath or reinforcement extends over the front of the backing formed by the corrugated sheet 10 and is secured to the backing by staples 16 which extend through the backing and have their prongs bent around the meshes of the lath for convenience in handling the base. The lath and backing are secured together before the base is applied

to a building, so that the backing and lath may be applied as a unit to the usual studs 12 or other part of a building, being usually secured thereto by staples 13. In practice, the assembled sheets of the base usually extend horizontally, so that the base may be applied in large sections.

A characteristic of the present invention is that the backing has a corrugated front face which is contiguous to the back of the lath, so that the plaster 14 applied through the lath will fill the grooves in the corrugated sheet 10 and will be well bonded to the base. The backing thus formed is exceptionally light in weight, efficient in operation and provides a channelled formation for the plaster rearwardly of the lath. Whilst woven wire lath or reinforcement has been described, it will be understood that other kinds may be used in lieu thereof.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. A plaster base composed of waterproofed corrugated board having a corrugated sheet on the front thereof and wire lath secured to the outer face of said board, comprising wires substantially parallel with the corrugated board and obliquely woven wires between the parallel wires.

2. A plaster base composed of waterproofed corrugated board and wire lath secured thereto comprising wires substantially parallel with the corrugations of the board and obliquely woven wires between parallel wires, said corrugated board comprising a double faced corrugated sheet and an exposed corrugated sheet contiguous to the lath.

Signed at Chicago, Illinois, this 6th day of May, 1922.

WALTER H. FAIRCHILD.
